United States Patent Office.

JOSEPH A. MILLER, OF NEW YORK, N. Y.

Letters Patent No. 73,362, dated January 14, 1868.

IMPROVEMENT IN APPARATUS FOR SINGEING COTTON CLOTH.

The Schedule referred to in these Letters Patent and making part of the same.

TO ALL WHOM IT MAY CONCERN:

Be it known that I, JOSEPH A. MILLER, of the city, county, and State of New York, have invented a new and useful Improvement in Apparatus for Singeing Cotton Cloth and other Webs; of which the following is a full, clear, and exact description, reference being had to the accompanying drawing, forming part of this specification, and in which—

Figure 1 represents a plan of a singeing-apparatus constructed according to my improvement,

Figure 2 a longitudinal section thereof, and

Figure 3 a transverse section of the same.

Similar letters of reference indicate corresponding parts.

In manufacturing cotton goods, it is usual to singe them prior to bleaching, for removal of the downy fibre which protrudes or projects from their surface.

My invention consists in combining with a rotary heating-cylinder or cylinders a reflector, to prevent loss of heat by radiation; likewise in the use of a damper for regulating the heat in or to the singeing-surface.

Referring to the accompanying drawing, A represents the fireplace of the apparatus, B the ash-pit, and C the escape-pipe or chamber, with an outlet, a. Connecting the fireplace A and escape-chamber C, is a flue or singeing-surface, D, of more or less cylindrical character, and hung loose or free, preferably on rollers b, so as to be capable of turning or having a curvilinear motion given to it, and which may be produced by a crank, c, operating a pawl, d, made to bite on or gearing with a ratchet-wheel, e, attached to the cylinder or flue D, that may be held from working backwards by a spring, f.

By this arrangement it will be seen that not only may the web be swept over the singeing-surface with increased facility and dispatch, but that a uniformity of heat is secured over the top and sides of said surface, where the cloth is brought in contact with it, and by the continual or frequent motion of the cylindrical singeing-surface or flue D, the same may be made comparatively thin or light, and of uniform thickness, no part remaining permanently uppermost, which construction, it will be obvious, largely economizes the consumption of fuel. By duplicating these flues, that is, using two, arranged side by side, the cloth may be singed on both sides at once, by passing it under one of such flues or singeing-surfaces and over the other, which will be found very advantageous in singeing printed goods and delaines.

In using the terms "rotary," or "rotating," or "curvilinearly moving" to the singeing-surface D, made more or less of a cylindrical character, whether the same form a flue or not, of course is meant or included either a continuous or intermittent motion in one direction, or oscillating movement, so that the surface exposed to abstraction of heat by the cloth is being constantly or frequently varied.

To prevent loss of heat by radiation from the flue D, it is furnished underneath with a reflector, E, which further contributes to economy in working. Said apparatus is also shown as provided with a movable plug or other damper, F, to the singeing-flue, at its rear end, whereby the temperature of said flue may be directly controlled to suit different descriptions of work, or otherwise to modify the heat of the flue according to circumstances.

What is here claimed, and desired to be secure by Letters Patent, is—

1. In combination with a rotating singeing-body or surface, the reflector E, substantially as described.
2. The combination of a damper, F, with a rotating singeing-body or surface, essentially as specified.

JOSEPH A. MILLER.
